MULTIPLE POWER WRENCH

Walter Hall, Los Angeles, Calif., assignor of one-half to J. Michael O'Meara, Los Angeles, Calif.

Application June 26, 1935, Serial No. 28,529

18 Claims.

(Cl. 81—57)

This invention relates to a power tool and relates more particularly to a multiple power wrench for turning or tightening securing members such as nuts, bolts, studs, screws, etc. A general object of the present invention is to provide a simple practical power wrench that is operable to simultaneously and properly tighten a plurality of securing members such as nuts, bolts, studs, screws and the like, to connect machine parts, etc.

Another object of this invention is to provide a multiple power wrench that is operable to turn a plurality of nuts, bolts or like securing members until they are hand tight or tighter and then automatically turn the securing members to a desired or selected final degree of tightness. The tool of the present invention in simultaneously turning down the securing members to hand tightness or tighter, to take the slack out of the parts before turning the members to their final tight or set positions, prevents tilting, straining, distorting and binding of the machine parts being connected and assures the proper connecting of the parts.

Another object of this invention is to provide a multiple power wrench that is operable to turn down or tighten a plurality of nuts, bolts, studs or other securing members to a uniform selected or predetermined degree of tightness and no tighter, so that there is no danger of stripping the threads or straining or distorting the connected parts or causing uneven or improper connecting of the parts.

Another object of this invention is to provide a multiple power wrench of the character mentioned that may embody a sufficient number of chucks or sockets for engaging of the nuts, studs, bolts, or the like, in a series of such securing members for connecting machine parts or the like, so that it is operable to rapidly and finally connect the machine parts or assembly in one simple operation.

Another object of this invention is to provide a multiple power wrench of the character mentioned simultaneously turn the nuts, bolts, studs or other securing members to hand tightness or slightly tighter to take up the slack and then successively partially turn the diametrically opposite securing members of the series until all of the several securing members are tightened to a desired degree thus assuring the equal or uniform tightening of the securing members and preventing tilting and distorting of the parts being connected.

Another object of this invention is to provide a multiple power wrench of the character men-

tioned that embodies a novel and particularly effective transmission or drive for simultaneously rotating the socket carrying spindles to turn the securing members to hand tightness or tighter that is automatically responsive to the resistance offered by the separate or individual securing members to selectively cease rotating the spindles as the securing members are turned down to hand tightness or tighter.

Another object of the invention is to provide a multiple power wrench of the character mentioned that embodies a novel and particularly effective clutched drive or transmission for successively turning spaced or diametrically opposite socket carrying spindles until the nuts, bolts or securing members engaged by the sockets have been tightened to the desired degree of tightness, which drive or transmission is responsive to the resistance offered to turning by the individual or separate securing members to selectively cease the turning of the spindles as the securing members are tightened to the desired final degree of tightness.

Another object of this invention is to provide a multiple power wrench of the character mentioned in which the drive or transmission for turning the spindles to turn down the securing members to their final degree of tightness includes a novel clutch that is adjustable to provide for the final tightening of the securing members to any selected or desired degree of tightness.

Another object of this invention is to provide a multiple power wrench that includes means for automatically locating or centering the wrench when it is brought against the work or parts being connected whereby the chucks or sockets may be quickly and properly engaged with the nuts, bolts or other securing members on the parts.

Another object of this invention is to provide a power tool of the character mentioned in which the spindles are simultaneously adjustable by a simple adjusting means to engage their chucks or sockets with securing members having different relative spacings and with members that are difficult of engagement or access.

Another object of the invention is to provide a power wrench of the character mentioned in which the clutches automatically release when the securing members have been set up or turned down to the desired degree of tightness and upon releasing give audible indications to the operator so that he may cut off the power and remove the wrench from the work for further use.

Another object of this invention is to provide a multiple power wrench of the character men-

tioned that is easy and convenient to operate and whose use and operation do not require the exercise of great care or skill.

5 A further object of this invention is to provide a multiple power wrench of the character mentioned that is in the form of a small compact self-contained portable unit.

10 The various objects and features of my invention will be fully understood from the following detailed description of typical forms and applications of my invention throughout which description reference is made to the accompanying drawings, in which:

15 Fig. 1 is a central longitudinal detailed sectional view of one form of the invention illustrating it in operative position on an assembly of parts being connected. Fig. 2 is a transverse detailed sectional view taken substantially as indicated by line 2—2 on Fig. 1. Fig. 3 is an enlarged transverse detailed sectional view of one of the chucks or sockets being a view taken substantially as indicated by line 3—3 on Fig. 1. Fig. 4 is an enlarged fragmentary detailed sectional view taken substantially as indicated by line 4—4 on Fig. 2. Fig. 5 is a central longitudinal detailed sectional view of another embodiment of the invention. Fig. 6 is a transverse detailed sectional view taken substantially as indicated by line 6—6 on Fig. 5. Fig. 7 is a fragmentary transverse detailed sectional view taken as indicated by line 7—7 on Fig. 5 and Fig. 8 is an enlarged transverse detailed sectional view taken as indicated by line 8—8 on Fig. 5.

20 The form or embodiment of the present invention illustrated in Figs. 1 to 4, inclusive, of the drawings, includes generally a body 10, a plurality of rotatable socket carrying spindles 11 projecting from the body 10, means 12 for centering or locating the tool on the work or parts being connected, and an automatically clutched compound drive 13 for rotating the spindles 11.

25 The body 10 houses the transmission or drive 13 and forms a carrier for the spindles 11. The body 10 may comprise two plates, an inner plate 14 and an outer plate 15. A ring or shell 16 is arranged between the outer or peripheral portions of the plates 14 and 15 to space the plates and form the outer wall of the body. Bolts 18 pass through openings in the spaced end plates 30 50 14 and 15 and nuts 17 are threaded on the bolts to maintain the plates and the shell 16 in the assembled relationship. The body constructed as just described has a cylindrical interior or opening 19. Means may be provided for suspending the body 10 and associated parts from an overhead support. In the particular structure illustrated in the drawings the suspension means includes a hanger plate 20 bowed or curved to conform to the upper surface of the body shell 16. 55

60 Screws 21 extend through slots 22 in the plate 20 and openings in the shell 16 to adjustably connect the plate 20 to the shell. Nuts 23 may be threaded on the screws 21. A central perforated lug or eye 24 projects from the plate 20 to receive the end part of an extensible spring 26 carried by a cable or line 27. The line 27 may be connected to a counter-balance or other means not shown, so that the wrench may be swung or shifted about as required. Suitable curved handles 28 project from the opposite side portions of the body shell 16 to facilitate the manipulation of the wrench.

65 The spindles 11 are provided to carry chucks or sockets 30 for engaging the nuts, bolts, screws or other securing parts to be tightened or turned down by the wrench. The spindles 11 extend

70 through openings 31 in the inner body plate 14 and project axially or longitudinally from the plate relative to the central longitudinal axis of the body 10. The spindles 11 extend through the body cavity or opening 19 and their end portions 75 are rotatably carried in openings 32 in the outer plate 15. The plates 14 and 15 are preferably thickened or provided with bosses at their openings 31 and 32 so that the spindles 11 have extensive bearing on the plates. The spindles 11 10 are preferably spaced some distance inwardly from the periphery of the body 10 as illustrated in Figs. 1 and 2 of the drawings.

15 The invention contemplates the provision of one or more spindles as may be required for the particular purpose for which the wrench is intended. In the tool illustrated in the drawings there are six spindles 11 projecting from the inner plate 14 of the body, it being understood that there may be fewer or more spindles 11 as 20 required. The spindles 11 may be provided with universal joints U intermediate their ends to facilitate the more ready engagement of the sockets 30 with the securing members or parts. The joints U are preferably comparatively stiff so that 25 the outer parts or sections of the spindles do not fall or move by gravity. The spindles 11 may be equally spaced circumferentially about the axis of the wrench so that their sockets 30 may engage an annular series of equally spaced nuts or 30 the like, it being apparent that the spacing of the spindles 11 may be varied to suit various conditions of operation. The length of the spindles 11 or the extent of the projection of the spindles 11 35 from the body plate 14 depends upon the particular use or application of the wrench. In Fig. 1 of the drawings the wrench is shown in position to tighten down the nuts 33 of the hub bolts or drum bolts 34 of a wheel W and the spindles 11 are sufficiently long to properly engage their 40 sockets 30 with the nuts 33 when the locating or positioning means 12 engages the axle or hub H as will be hereinafter described.

45 The chucks or sockets 30 are provided on the outer ends of the spindles 11 in concentric or axial relation thereto. In accordance with the invention the chucks or sockets 30 are shiftable axially on the spindles so that they may individually conform to or properly engage with nuts 33, which may be different distances from the 50 work which may be a drum or wheel W when the wrench is first applied to the work. Longitudinal openings 35 in the chucks or sockets 30 shiftably receive the spindles 11 and keys, screws 36 or other such means on the sockets operate 55 in grooves 37 in the spindles 11 to connect the sockets with the spindles for rotation therewith. The screws 36 may engage the ends of the grooves 37 to limit the longitudinal movement of the sockets on the spindles. Springs 38 are provided 60 in the openings 35 and are arranged under compression between the ends of the spindles 11 and the bottoms of the openings to yieldingly urge the sockets 30 outwardly on the spindles. Polygonal openings or sockets 40 are provided in the 65 outer ends of the chucks or sockets 30 to receive the nuts 33. The sockets 40 may have a large number of flat faces or walls to have non-rotatable engagement with the nuts 33 with a minimum of manipulation or turning between the 70 sockets 30 and the nuts. It is to be understood that when the tool is to be employed to tighten screws the spindles 11 are provided with screw driver bits.

75 The means 12 for centering or locating the 75

power wrench is such that the wrench may be brought against the work or parts to be connected and quickly positioned where the sockets 30 of the several spindles 11 properly receive or engage with the nuts 33. The centering or locating means 12 includes an axial or concentric tube 41 at the inner side of the body 10. In the simple form of the invention shown in the drawings the tube 41 is attached directly to the plate 14 as by welding. A socket or cup 42 is shiftable in the tube 41 and its outer portion projects from the tube. The cup 42 is shaped and proportioned to receive a part of the work or machine assembly being worked on. In the particular application of the invention shown in the drawings the cup 42 is adapted to receive a hub cap or hub part 43 which is concentric with respect to the circular or annular series of nuts 33. A spring 44 is arranged in the tube 41 between the closed inner end of the cup 42 and the body plate 14. The spring 44 is a spiraled or helical spring and its inner convolution has an end wrapped about or otherwise secured to a bolt or rivet 46 on the body plate 14. The end part of the outer convolution of the spring 44 is secured to the cup 42 by a screw 46. The spring 44 is adapted to yield to permit limited movement between the wrench and the work or machine assembly being worked upon when the wrench is applied to the assembly and during operation of the wrench. It is believed that it will be apparent how the wrench may be moved to a position where the cup 42 is passed over the hub part 43 to position the wrench where it is concentric with the series of nuts 33 and thus greatly facilitate the proper engagement of the chucks or sockets 30 with the nuts 33. The sockets 30 on two diametrically opposite spindles 11 may project ahead of the other sockets 30 so that one or both of these leading sockets may be first engaged with the nuts 33 and thus align the other sockets with the other nuts and greatly facilitate the engagement of the several sockets 30 with the nuts.

The drive 13 is housed in the body 10 and forms a clutched transmission between a suitable power drive D and the several spindles 11. The prime mover or power means may be directly connected with the wrench in which case it may directly drive or operate the drive 13. In the particular form of the invention being described the power drive D which enters the outer side of the body 10 at its center may be considered as extending from a power means at a suitable remote point. A shaft 47 is rotatable in central or axial openings 48 in the body end plates 14 and 15. The plates 14 and 15 are preferably enlarged at the openings 48 to provide ample support or bearing for the shaft 47. The particular drive D illustrated comprises a flexible shaft or flexible drive 60 which may be rotated by any suitable power means and which is connected with the central shaft 47 of the wrench.

The compound clutched transmission or drive 13 of the present invention includes gears or pinions 50 on the spindles 11 and a driving element E for turning the pinions 50. A pinion 50 is provided on each spindle 11 in the body opening 18. Feathers or keys 51 connect the pinions 50 and the spindles 11 against relative rotation. The several pinions 50 are preferably of equal effective diameter. The driving element E is provided on the central shaft 47 and rotates with the shaft in the body opening 18. The element E includes a plate or block 52 connected to the shaft 47 to turn therewith. In the simple form

of the invention disclosed the block 52 is fixed to the shaft 47 by a pin 53. The block 52 projects radially from the shaft 47 and has two stub shafts or trunnions 54. The trunnions 54 are equally spaced from the shaft 47 and their axes are parallel with the axis of the shaft. The element E includes pinions or gears 55 rotatably supported on the trunnions 54. The gears 55 are of equal diameter and their teeth are adapted to mesh with the teeth of the pinions 50 as the element rotates. The teeth of the gears 55 may be sharp, as illustrated, or the teeth of the pinions 50 may be sharp to insure the proper engagement of the teeth of the gears and pinions. It will be seen that during rotation of the element E the gears 55 successively come into meshing cooperation with diametrically opposite pinions 50. The gears 55 are preferably removable so that one of the gears may be removed and the number of spindles 11 reduced, say to one or two spindles, adapting the wrench to be operated or driven by a small motor.

The drive 13 includes an adjustable automatic clutch means normally preventing rotation of the gears 55 about their individual axes so that engagement of their teeth with the teeth of the pinions 50 causes successive advancement or partial rotation of the pinions 50 which clutch means is yieldable or releasable to permit independent rotation of the gears 55 when the resistance to turning of a pinion 50 offered by a tightened down nut 33 exceeds a definite limit. The automatic adjustable clutch means includes two leaf springs or flexible members 56 carried by the driving element E. These members 56 may each comprise one or more laminae or spring sections. Studs 57 project from opposite sides of the block 52 and extend through openings in the flexible members 56 to support the members on the block. Nuts 58 are threaded on the studs 57 and engage the flexible members 56 to hold the members in their operative positions and to regulate the action of the members as will be hereinafter described. Lock nuts 59 are threaded on the studs 57 to lock the adjusting nuts 58 in their set positions. Lugs or teeth 60 project from the inner sides of the flexible members 56 to fit between or cooperate with the teeth of the gears 55. There may be two teeth 60 on each flexible member 56, one for cooperating with the teeth of one gear 55 and the other for cooperating with the teeth of the other gear 55. The engagement of the clutch teeth 60 with the teeth of the gears 55 normally prevents independent rotation of the gears 55 about their axes so that meshing of the gears 55 with the pinions 50 during rotation of the drive element E causes successive partial turning of the pinions 50 in a direction to tighten the nuts 33.

When a nut 33 is tightened down to a desired degree of tightness it offers resistance to rotation of the pinion 50 with which it is associated, by its socket 30 and spindle 11, and upon a gear 55 moving into mesh with this pinion 50 the meshing of the teeth of the gear and pinion thus held against rotation results in a torque being placed on the gear 55 which overcomes the resiliency of the flexible members 56 so that the members are flexed outwardly allowing the teeth of the gear 55 to ratchet past the teeth 60. Thus the gear 55 passes the said pinion 50 without advancing or turning the pinion and, therefore, without further tightening of the tightened down nut 33. The sound or noise produced by the ratcheting of the gear 55 past the teeth 60 audibly

5 indicates to the operator that a nut 33 has been tightened down to the desired degree. From the above it will be seen that the resistance to independent rotation of the gears 55 about their axes offered by the flexible members 56 determines the degree of tightness to which the nuts 33 are tightened.

10 The invention provides for the ready regulation of the resilient resistance offered by the flexible members 56 to the independent rotation of the gears 55 about their axes. Openings 61 are provided in one or both of the plates 14 and 15 rendering the nuts 33 and 58 accessible for turning or threading. It will be apparent how 15 longitudinal adjustment of the nuts 33 on the studs 57 regulates the setting of the members 56 and the resistance to independent turning of the gears 55 offered by the members 56. Accordingly, the nuts 33 comprise means for regulating 20 or adjusting the clutch means to provide for the tightening of the nuts 33 to any desired or selected degree of tightness.

25 It is a feature of the invention that the drive 13 includes an operative interconnection or drive between the several spindles 11 to assure the rapid tightening of the nuts 33 to hand tightness or tighter during the initial phase of the operation of the wrench. This interconnection or 30 drive of the compound drive 13 includes spools or pulleys 62 on the spindles 11. In the simple construction illustrated in the drawings the pulleys 62 are parts or end extensions of the pinions 58. The pulleys 62 are of the same effective diameter. A continuous belt 63 engages around or 35 over the several pulleys 62. The belt 63 may be retained on the pulleys 62 by the inner sides of the pinions 58 and the inner surface of the body plate 14. The belt 63 trained over the pulleys 62 forms a drive between the several pinions 11 and 40 when the gears 55 engage and turn two diametrically opposite pinions 58 during the initial stages of operation of the wrench the belt 63 drives or turns the several other spindles 11 so that the nuts 33 are each given a partial tightening rotation each time the gears 55 engage a pair of pinions 58. When the nuts 33 have been turned to hand tightness or tighter the nuts 33 offer such 45 resistance to rotation of the spindles 11 that the belt 63 slips on the pulleys 62 without transmitting rotation to the spindles 11.

50 The invention provides means for regulating the tautness of the belt 63. A bolt 64 extends through radial slots 65 in the body plates 14 and 15 and carries a rotatable roller 66 for engaging the belt 63. The roller 66 may engage or bear on either the outer side or the inner side of the belt 63. A setting or tightening nut 67 is threaded on one end of the bolt 64. By shifting the bolt 64 in the slots 65 the roller 66 may be made 55 to bear against the belt 63 with greater or less pressure and thus movement of the bolt 64 adjust the tautness of the belt 63 and determines the degree of tightness to which the nuts 33 are turned by the transmission of force through the 60 belt 63.

65 The operation of the wrench shown in Figs. 1 to 4 is as follows: The nuts 33 are first started on the studs or bolts 34 by hand or in any other desired manner. The power wrench is then 70 brought to a position where the cup 42 receives or engages over the hub part 43. The engagement of the cup 42 with the hub part positions or locates the wrench where its sockets 38 may engage the nuts 33. When the sockets 38 have 75 been properly engaged with the nuts 33 the power

means may be started or the flexible drive D connected or clutched with the source of power. The operator of the wrench may engage or hold one or both of the handles 28 during the operation of the wrench to prevent disengagement of the sockets 38 from the nuts 33. The springs 38 yield to permit the engagement of the sockets with nuts 33 that may be at varying distances from the face of the work W and the springs urge the sockets 38 against the nuts with sufficient pressure to insure the proper cooperation of the sockets with the nuts.

75 Rotation of the drive D of course causes rotation of the driving element E. As the element E rotates the teeth of its two gears 55 successively come into meshing engagement with diametrically opposite pinions 58 or pinions 58 at opposite sides of the series of pinions. The teeth 60 on the flexible members 56 hold the gears 55 against independent rotation during the initial phases 20 of operation of the tool so that the gears 55 operate to impart partial rotation to the pinions 58 as they engage with the pinions. The belt 63 trained over the pulleys 62 forms a drive between the several spindles 11 during the free or initial 25 threading in of the nuts 33 causing the several spindles 11 to each receive a partial turn or rotation each time the gears 55 mesh with or turn to diametrically opposite pinions. Thus the belt 63 interconnects or forms a connecting drive between the several spindles 11 and provides for the rapid threading of the several nuts 33 to hand tightness or tighter. When a nut 33 has been tightened down to hand tightness or tighter it offers such resistance to rotation of the spindle 35 11 carrying the socket 38 engaging it that the belt 63 slips on the said pulley 62 without causing further rotation of the spindle. As described above, the bolt 64 may be shifted to regulate the tautness of the belt 63 and thereby 40 regulate or determine the degree of tightness to which the nuts 33 are turned through the action of the belt 63 and the degree of tightness at which the belt slips on the pulleys 62. As the belt 45 partially turns or tends to partially turn all of the spindles 11 each time the gears 55 partially turn two of the pinions 58 the several nuts 33 are soon tightened to hand tightness or tighter depending upon the tautness of the belt 63, at which time the belt 63 ceases to function. The 50 belt 63 thereafter merely slips on the pulleys 62.

55 The continued rotation of the driving element E successively brings its gears 55 into driving or turning engagement with diametrically opposite pinions 58 to successively partially thread in two diametrically opposite nuts 33. The spring members 56 are usually or preferably adjusted or set by the nuts 33 so that the engagement of their teeth 60 with the teeth of the gears 55 offers substantial resistance to independent rotation of the gears about their axes. Thus the gears 55 operate as tooth driving parts of the element 11 to partially turn the pinions 58 and their spindles 11 until the nuts 33 are tightened down to a substantial or selected degree of tightness. The 60 progressive successive partial turning of two diametrically opposite spindles 11 as described above of course results in progressive and successive tightening of pairs of diametrically opposite nuts 33. The nuts 33 being tightened down 70 in this manner do not cause straining, binding or distorting of the parts being connected.

75 When a nut 33 has been turned down to a selected degree of tightness it offers such resistance to rotation of the spindle 11 with which it is con- 75

nected that the torque imposed on the gear 55 meshing with the pinion 50 on that spindle overcomes the pressure and resiliency of the spring members 56 to flex the members outwardly and cause the gear 55 to turn or ratchet past the teeth 60. The teeth of the gear 55 turning or ratcheting past the teeth 60 produce a sound to audibly indicate to the operator that a nut 33 has been tightened down to its final position. The nuts 33 are successively or independently tightened to the selected degree of tightness in this manner, it being noted that the several nuts 33 are each independently finally tightened and that the nuts are all tightened to the same degree of tightness. As described above, the setting or adjustment of the flexible members 56 determines the degree of tightness to which the nuts 33 are finally turned. When the operator notes that the wrench no longer causes turning or rotation of any of the spindles 11 the rotation of the drive D is stopped and the wrench is removed from the work.

The form of power wrench illustrated in Figs. 5 to 8, inclusive, of the drawings includes, generally, a body 10, a plurality of chuck or socket carrying spindles 11 adjustably carried by the body 10, means 72 for adjusting the spindles 11 and a drive 73 in the body 10 for driving or turning the spindles 11.

The body 10 may be similar, generally, to the body 10 described above comprising two end plates 14 and 15 and an annular shell 76 arranged between the outer or peripheral portions of the plates. Screws 77 may attach the plates 14 and 15 to the shell 76. The body 10 constructed as just described has a comparatively large internal space or opening 78. Suspension means 80 similar to the means for suspending the previously described form of wrench may be provided on the body 10 for suspending the wrench from a suitable overhead support. A plurality of housings or cups 81 project from the plate 15. The number and position of the cups 81 depends upon the number and position of the spindles 11. In the particular case illustrated there are five equally spaced housings or cups 81 arranged in an annular or circular series on the inner side of the plate 15. Suitable handles 82 may project from the body shell 76 at opposite sides of the body.

The spindles 11 carry chucks or sockets 83 at their outer ends for engaging nuts, bolts, studs or like securing members. In the simple construction illustrated the sockets 83 are fixed to the spindles 11 by pins 84 it being apparent that the sockets 83 may be shiftably on the spindles in the same manner as the sockets 30. The chucks or sockets 83 have polygonal sockets 85 in their outer ends for receiving nuts, the heads of bolts, screws or the like. The sockets 83 preferably engage the securing members with some clearance or freedom of movement so that the sockets 83 may be slightly angularly disposed relative to the securing members. The spindles 11 project from the ends of the cups 81 and are tiltable or adjustable relative to the cups. Collars 86 fixed on the spindles 11 within the cups 81 have spherically curved parts 87 shiftably bearing in correspondingly shaped openings 88 in the end walls of the cups 81. The engagement of the parts 87 in the openings 88 is such that the spindles 11 may tilt or have universal movement in the openings.

The means 72 for adjusting the spindles 11 is such that the spindles may be simultaneously shifted inwardly or outwardly relative to the central longitudinal axis of the wrench to facilitate

the engagement of the sockets 83 with the nuts or securing parts. The adjusting means 72 includes a member 90 arranged against the outer surface of the plate 78 and having a tubular part 91 extending through central openings 92 in the plates 14 and 15. A nut 93 is threaded on the projecting outer end of the part 91 to secure the member 90 to the body. The member 90 has a plurality of spaced projecting arms 94. The inner portions of the arms 94 are outwardly divergent 10 while the outer end portions of the arms extend laterally or radially outwardly as shown in Fig. 5 of the drawings. The arms 94 have openings 95 rotatably receiving or passing the spindles 11 adjacent the ends of the cups 81. The arms 94 15 are flexible and normally tend to spring outwardly through their resiliency to tilt the spindles 11 to outwardly flaring or divergent positions.

Means is provided for contracting or moving the arms 94 inwardly. A shiftable stem 96 extends longitudinally through the opening 97 in the part 91 and carries a head 98 located between the flaring inward parts of the arms 94. A handle 99 may be provided on the end portion of the stem 96 projecting beyond the nut 93. A ring 100 surrounds the inner portions of the arms 94 and is connected with the head 98 by fingers 101 passing between the spaced arms 94. When the stem 96 is pulled to move the ring 100 toward the body plate 78 the arms 94 are 30 allowed to spring outwardly to move or tilt the spindles 11 outwardly. When the stem 96 is pushed inwardly to move the ring 100 away from the plate 78 the ring 100 contacts the flaring inner portions of the arms 94 to spring or flex 35 the arms inwardly and thus tilt the spindles 11 inwardly or toward the central longitudinal axis of the wrench.

In the use or application of the wrench illustrated in Figs. 5 to 8 of the drawings the tool 40 is intended to tighten nuts 103 threaded on the bolts 104 of a wheel drum 105. The hub 106 of the wheel projects from the drum 105 and surrounds the series of nuts 103. The wall of the hub 106 is inclined or outwardly convergent 45 making it difficult to engage the nuts 103. To engage the sockets 83 with the nuts 103 the stem 96 is pushed inwardly so that the ring 100 flexes the arms 94 inwardly to bring the spindles 11 to positions where the sockets 83 may be 50 readily entered or passed into the hub 106. After the sockets 83 have been located in the hub 106 adjacent the nuts 103 the stem may be pulled outwardly to permit the arms 94 to spring outwardly and bring the sockets 83 in positions to 55 engage the nuts 103. If desired the wrench shown in Figs. 5 to 8, inclusive, of the drawings may have a means for centering or locating the wrench similar to the above described means 12. In the event a centering or positioning means similar to the means 12, is provided on the wrench it may be mounted on the body 10 through a yoke, bracket, or the like so that it does not interfere with the spindle adjusting means 72 just described. A spindle adjusting means similar to the means 12 may be provided on the wrench shown in Figs. 1 to 4 in which case its operating stem 96 may be spaced from the center of the wrench where it does not interfere with the centering means 12.

The transmission or drive 73 is operable to simultaneously rotate the several spindles 11 to turn the nuts 103 to a definite and equal degree of tightness. The drive 73 includes a rotatable driving element 108 in the body opening 78, pin- 75

ions 109 adapted to be rotated by the element 108 and clutches C between the pinions 109 and the spindles 71. The driving element 108 may be in the nature of a ring gear or spur gear meshing with the several pinions 109. In the case illustrated the element 108 is a ring gear rotatably bearing on the inner surface of the body shell 78. The pinions 109 are arranged in the body opening 78 in axial alignment with the housings or cups 87 to have meshing engagement with the element 108. The pinions 109 are provided with shafts or trunnions 110 rotatable in the openings of bosses 111 projecting from the body plate 74. One of the pinions 109 constitutes a driver for the element 108. The trunnion 110 of the driver pinion 109 is elongated to project through its boss 111 and has a polygonal socket 112 receiving a polygonal part 113 on a flexible drive 114. It will be apparent how rotation of the driver pinion 109 by the drive 114 causes rotation of the driving element 108 and thus causes simultaneous rotation of the several pinions 109.

The clutches C form operating or driving connections between the pinions 109 and the spindles 71 and are automatically and independently releasable when the nuts 103 have been turned to a desirable degree of tightness. Each clutch C includes a clutch plate or disc 116 attached to a pinion 109. The discs 116 have parts 30 extending through and rotatably bearing in openings 117 in the body plate 78 whereby the pinions 109 each have rotatable bearing on the two body plates 74 and 78. A complementary and opposing disc 118 cooperates with each disc 116. The discs 118 are arranged in the cups 87 and are urged against the discs 116 by springs 119 bearing against the collars 86. The clutch discs 116 and 118 have engaging or meshing parts 120 for transmitting rotation. The engaging edges or sides of the clutch parts 120 are inclined or pitched to slip one on the other when the clutches C are subjected to sufficient torque to overcome the pressure exerted by the springs 119.

45 Universal or slack connections are provided between the outer clutch discs 118 and the spindles 71. The connections may include extensions 121 on the spindles 71 freely or loosely fitting sockets 122 in the discs 118. Pins 123 carried by the discs 118 extend through transverse slots 124 in the spindle extensions 121 and are preferably diametric with respect to the centers of curvature of the parts 87. The pins 123 have extensive clearance in the slots 124 and are shiftable axially or longitudinally in the slots to permit relative longitudinal movement between the spindles 71 and the clutch discs 118.

In the operation of the form of wrench shown in Figs. 5 to 8 of the drawings the wrench is first brought to a position where its sockets 83 may be entered in the open outer end of the hub 106. The handle 98 may be pushed inwardly causing the cooperation of the ring 100 with the divergent inner portions of the arms 94 to bend the arms inwardly and thus move the spindles 71 inwardly. Thus the spindles 71 may be brought to positions where their sockets 83 may be passed into the outer open end of the outwardly converging hub 106. The wrench is then moved to a position to bring the sockets 83 adjacent the nuts 103 whereupon the handle 98 may be pulled outwardly allowing the arms 94 to flex outwardly and bring the sockets 83 to positions where they may have turning engagements with the nuts 103. The springs 118 may yield to permit the spindles

71 to independently move to positions where their sockets 83 may properly engage the nuts 103 which may initially be spaced varying distances from the wrench body 70. The power means may be started or the drive 114 may be clutched with the power means to operate the wrench.

Rotation of the drive 114 results in rotation of the driving element 108, as described above, so that the several pinions 109 are simultaneously rotated. The springs 118 normally hold the discs 118 in clutching engagement with the discs 116 so that rotation of the pinions 109 causes rotation of the spindles 71. Rotation of the spindles 71 of course causes threading or tightening of the nuts 103. Thus the nuts 103 are simultaneously tightened down. When a nut 103 is tightened down to the extent that it offers sufficient resistance to rotation of a spindle 71 to impose a torque on the clutch of the spindle which overcomes the pressure of the spring 118 the disc 118 of that clutch moves outwardly away from the disc 116 and the clutch parts 120 become disengaged. It is to be understood that the several clutches C operate independently of one another and release when the separate or independent nuts 103 have been tightened to the desired degree. It will be understood, of course, that the degree to which the nuts 103 are tightened before the release of the clutches C depends upon the pitch or slope of the engaging sides of the clutch parts 120 and upon the pressure exerted by the springs 118. When the operator observes that the spindles 71 are no longer rotated the power means is stopped or the drive 114 is disconnected from the power means and the wrench is disengaged from the nuts 103. Following the disengagement of the sockets 83 from the nuts 103 the operator may push inwardly on the handle 98 to cause the arms 94 to be flexed inwardly and at the same time may move the wrench outwardly so that the sockets 83 may be moved outwardly from the hub 106.

Having described only typical preferred forms and applications of my invention I do not wish to be limited or restricted to the specific details herein set forth, but wish to reserve to myself any variations or modifications that may appear to those skilled in the art or fall within the scope of the following claims.

Having described my invention, I claim:

1. In a wrench for tightening a plurality of securing members, a plurality of rotatable spindles operable to transmit tightening forces to said members, and a transmission operable by a single drive to rotate the several spindles independently to tighten the said members to the same degree of tightness and no tighter, said transmission including pinions associated with the spindles, and an element rotated by the drive operable to successively cooperate with pairs of substantially opposite pinions to partially rotate the same.

2. A device for tightening a plurality of threaded members, a body, rotatable spindles carried by the body, means on the spindles for engaging the members to turn the same, means supporting the body for movement whereby the said means may be simultaneously brought into engagement with the threaded members, and a transmission in the body for rotating the spindles to turn the members to a desired degree of tightness, the transmission including a rotatable driving element, a drive for continuously rotating the element, a friction drive normally yieldingly operating the spindles from the drive element, pinions opera-

5 tively associated with the spindles and rotated by the element, and clutch means confined to the drive element for automatically interrupting the transmission of rotation between the element and the individual spindles as the individual members reach the desired degree of tightness.

10 3. In a wrench for tightening a plurality of securing members, a body, a plurality of rotatable spindles carried by the body to project in a single direction therefrom and arranged in spaced parallel relation, means supporting the spindles for rotation about relatively stationary axes, means on the spindles for engaging the members to turn the same, pinions on the spindles, a drive shaft, and an element rotated by the shaft and operable to successively cooperate with the pinions to turn the spindles.

15 4. In a wrench for tightening a plurality of securing members, a plurality of rotatable spindles, means on the spindles for engaging the members to turn the same, pinions on the spindles, a drive shaft, an element rotated by the drive shaft operable to successively engage the pinions to partially rotate the individual spindles, and means interconnecting the spindles for simultaneous partial rotation until the individual members offer a selected resistance to rotation of the spindles.

20 5. In a wrench for tightening a plurality of securing members, a plurality of rotatable spindles, means on the spindles for engaging the members to turn the same, pinions on the spindles, a drive shaft, an element rotated by the drive shaft operable to successively engage the pinions to partially rotate the individual spindles, and means interconnecting the spindles for simultaneous partial rotation until the individual members offer a selected resistance to rotation of the spindles, the last named means including pulleys on the spindles, and a belt trained over the pulleys.

25 6. In a wrench for tightening a plurality of securing members, a plurality of rotatable spindles, means on the spindles for engaging the members to turn the same, pinions on the spindles, a drive shaft, an element rotated by the drive shaft operable to successively engage the pinions to partially rotate the individual spindles, and means interconnecting the spindles for simultaneous partial rotation until the individual members offer a selected resistance to rotation of the spindles, the last named means including pulleys on the spindles, a belt trained over the pulleys, and means for adjusting the belt to turn the spindles until the members offer a selected resistance to turning.

30 7. In a wrench for tightening a plurality of securing members, a plurality of rotatable spindles operable to transmit tightening forces to said members, and a transmission operable by a single drive to rotate the several spindles, the transmission including, pinions on the spindles, a part rotated by the drive, a gear supported by said part for rotation and adapted to successively mesh with the pinions, and means preventing independent rotation of the gear whereby the gear is operable to successively partially turn the pinions and releasable when the individual members offer a predetermined resistance to rotation of their pinions.

35 8. In a wrench for tightening a plurality of securing members, a plurality of rotatable spindles operable to transmit tightening forces to said members, and a transmission operable by a single drive to rotate the several spindles, the transmis-

5 sion including, pinions on the spindles, a part rotated by the drive, a gear supported by said part for rotation and adapted to successively mesh with the pinions, means preventing independent rotation of the gear whereby the gear is operable to successively partially turn the pinions and releasable when the individual members offer a predetermined resistance to rotation of their pinions, and means for adjusting the said means to release when the members offer different degrees of resistance to rotation.

10 9. A wrench for tightening a plurality of threaded members including a body, a plurality of rotatable spindles carried by the body and operable to transmit tightening forces to the members, an operative interconnection between the spindles for transmitting rotation between the spindles and adapted to slip with respect to the individual spindles when the individual members offer a definite degree of resistance to turning of the spindles, and means for successively imparting partial rotation to the spindles and automatically de-clutched with respect to the individual spindles when the members offer a definite degree of resistance to rotation.

15 10. A wrench for tightening a plurality of threaded members including a body, a plurality of rotatable spindles carried by the body and operable to transmit tightening forces to the members, and a compound clutched transmission in the body for simultaneously imparting partial rotation to the several spindles until the members are hand tight or tighter and then operable to successively impart partial rotation to the spindles until the members are tightened to a selected degree of final tightness.

20 11. A wrench for tightening a plurality of threaded members including a body, a plurality of rotatable spindles carried by the body and operable to transmit tightening forces to the members, and a transmission in the body including pinions fixed on the spindles, a driven part, rotatable gears carried by the driven part at opposite sides of its axis of rotation and adapted to successively mesh with the pinions, releasable means for holding the gears against rotation about their independent axes whereby the engagement of the gears with the pinions causes partial rotation of the spindles, the releasable means being releasable when the members offer a predetermined resistance to rotation, pulleys fixed on the spindles, and a belt trained over the pulleys to form an interconnection between the spindles until the members are turned to a certain degree of tightness.

25 12. A wrench for tightening a plurality of securing members including, a plurality of spindles operable to transmit turning forces to said members, and a transmission for rotating the spindles including pinions on the spindles, a clutched driving element operable to successively partially rotate the pinions, and a drive between the several spindles operable to simultaneously transmit partial rotation to the spindles when a spindle is partially rotated.

30 13. A wrench for tightening a plurality of securing members including, a plurality of spindles operable to transmit turning forces to said members, and a transmission for rotating the spindles including pinions on the spindles, a drive shaft, a driving element freely carried by the shaft and free to rotate and operable by the shaft to successively partially rotate the pinions and a clutch member secured to the shaft to rotate therewith

and to releasably engage the drive element so that it rotates with the shaft.

14. A wrench for tightening a plurality of securing members including, a plurality of spindles operable to transmit turning forces to said members, and a transmission for rotating the spindles including pinions on the spindles, a clutched driving element operable to successively partially rotate the pinions, and belt drive between the spindles operable to transmit simultaneous partial rotation to the spindles as each spindle is partially rotated.

15. A wrench for tightening a plurality of securing members including a unitary body, a plurality of spindles rotatably carried by the body and operable to transmit tightening forces to said members, and a transmission carried by the body and operable by a single actuating member to rotate the several spindles, the transmission including a single automatic releasable clutch, and a drive between the clutch and the spindles including positive drive elements successively engaged so the spindles are successively positively driven from the clutch.

25 16. In a wrench for tightening a plurality of securing members, a plurality of rotatable spindles operable to transmit tightening forces to said members, and a transmission operable by a single drive element to rotate the several spindles to tighten the said members to the same degree of tightness and no tighter, the transmission including a single clutch for automatically interrupting the transmission of rotation from the drive ele-

ment to the spindles as the individual members reach the desired degree of tightness, pinions operatively connected with the spindles, a rotatable drive element driven through the clutch to successively cooperate with the pinions to successively positively drive them from the clutch.

17. A wrench for tightening a plurality of securing members including, a body, a plurality of spindles rotatably carried by the body, and a power transmission carried by the body operable by a single power operated member to drive the spindles, the transmission including, a single automatic releasable clutch, a friction drive between the clutch and the spindles to normally drive all of the spindles, and a positive drive means between the clutch and the spindles including successively engaged members through which the spindles are successively driven.

18. A wrench for tightening a plurality of securing members including, a body, a plurality of spindles rotatably carried by the body, and a power transmission carried by the body operable by a single power operated member to drive the spindles, the transmission including, a single automatic releasable clutch, a friction drive between the clutch and the spindles to normally drive all of the spindles, and a positive drive means between the clutch and the spindles including a drive gear operated by the clutch and driven gears on the spindles successively engaged and positively operated by the drive gear.

WALTER HALL.
